AUTOMATIC EDGE INKING MACHINES

Kenneth Charles Joseph Webster, Leicester, England, assignor to United Shoe Machinery Corporation, Boston, Mass., a corporation of New Jersey

Filed Oct. 4, 1960, Ser. No. 60,389

Claims priority, application Great Britain Oct. 10, 1959
5 Claims. (Cl. 118—252)

This invention relates to improvements in machines for performing an operation on a marginal portion of an unattached shoe sole. The term shoe is used herein generically as indicating outer footwear generally, and the term sole as including sole members such as insoles.

There is hereinafter described one convenient construction of machine provided by the invention and illustrative thereof, the illustrative machine being a machine for performing a finishing operation on a marginal portion of an unattached shoe sole, the machine being adapted to apply a coating, specifically ink, to a marginal portion of a sole and of the general character disclosed in United States Letters Patent No. 2,357,471 Jalbert.

The machine disclosed in said patent is provided with a freely rotatable inking roll and a pair of driven, frusto-conical feed rolls rotatable about axes each of which is inclined to the other and also inclined to the axis of the inking roll. The construction and arrangement of the feed rolls and inking roll is such that a sole presented to the machine is gripped in a vertically disposed position between the frusto-conical portions of the feed rolls and, through the edge of the sole engaging the periphery of the inking roll, is fed progressively through a curvilinear path in such a manner that a marginal portion of the sole may be progressively treated with ink without it being necessary for an operator of the machine to guide the sole during operation thereon by the machine.

Machines of this general character have proved generally satisfactory with many types of soles but with a sole having a pointed toe it often occurs that a marginal portion in the toe region is not operated on. This is due to the fact that when a pointed toe portion is fed past the inking roll, the sole is swung through a relatively large angle at a much faster rate than is the case when a rounded toe portion is being operated upon and the momentum thus imparted to the heelward portion of the sole tends to carry the sole away from the inking roll thereby leaving a marginal portion of the sole which follows the toe end portion untreated by the inking roll.

It is an object of the present invention to provide an improved machine for applying a coating to a marginal portion of an attached shoe sole in which means is provided for avoiding the disadvantage above noted.

With this object particularly in mind the illustrative machine is a machine of the type disclosed in the above noted patent and having a pair of driven feed rolls and a rotary inking roll so disposed that the sole presented to the machine is fed through the machine progressively in a curvilinear path. For soles having pointed toes the illustrative machine is provided with feed rolls of comparatively small diameter so that such a sole presented to the machine may be gripped as close as possible to its peripheral edge in the toe region as it is fed through the machine. The rolls are provided with conical faces to give the maximum amount of frictional gripping area. To assist the small rolls in feeding the work the inking roll is driven at a peripheral speed substantially the same as that of the edge of a sole in contact therewith.

As disclosed in the above patent the feed rolls are so inclined relatively to each other that there is a pronounced downward component of force which tends to push the ingoing portion of the edge face of a sole into contact with the inking roll. The illustrative machine is provided

2

with means effective when the marginal portion of the pointed toe of such a sole is being operated upon to counteract the swinging action of the sole sufficiently to prevent the sole from leaving contact with the inking roll without otherwise materially affecting the feeding action of the machine.

The said means comprises a follower roll yieldably mounted on the machine in such a manner that during operation on the sides of a sole the follower roll engages and follows its edge contour while exerting but little force thereagainst. As the toe end of the sole is being operated on by engagement with the inking roll, its heel end is swung upwardly while the follower roll rides out of engagement with the sole and moves to a predetermined position to be engaged by the ingoing edge on the sole forepart (on the opposite side to that initially engaged by the roll) as the heel end moves over its topmost position and starts to descend. The follower roll thus yieldably decelerates the swinging movement of the sole, the spring action being at a maximum when contact of the sole with the roll occurs and decreasing as displacement of the roll increases as the sole continues to be fed through the machine, the roll again following the contour of the waist and side portions of the sole.

In order that the above and other of the various objects of the invention may become more clear there will now be given, with reference to the accompanying drawing, a more detailed description of the illustrative machine hereinbefore referred to.

In the drawings,

FIG. 1 is a side elevation of part of the illustrative machine, having some associated parts removed for the sake of clarity; and,

FIG. 2 is a fragmentary end elevation showing the relation of the feed wheels to the inking roll.

The preferred embodiment of the invention is directed to a machine of the general character disclosed in the above noted United States Patent No. 2,357,471 and only those parts that are new and those parts associated therewith will be herein referred to, a more complete understanding of the whole machine being had by reference to that patent.

The illustrative machine is provided with a pair of feed rolls 2 between which a sole S presented to the machine is gripped. Only one of the feed rolls is shown in FIG. 1 the other being removed for clarity. So that a sole having a pointed toe may be gripped as close as possible to its peripheral edge in the toe region the rolls 2 are comparatively small in diameter. The feed rolls 45 are arranged and driven in a similar manner to the feed rolls 10 and 12 referred to in said patent. The feed rolls 2 have conical faces between which the sole S is gripped in a substantially vertical plane. As disclosed in said patent and as seen in FIG. 2 the feed rolls are 50 tilted away from each other so that only the lower work-engaging portions of the conical surfaces are substantially parallel and grip the work in the machine, the axes of the rolls also being so inclined to each other that the work is gripped in the region "b" indicated in FIG. 1, i.e., 55 in advance of the lowermost point of the feed rolls (considered in the direction in which they are driven).

The machine is provided with an inking roll 4 mounted on a substantially horizontal shaft 6 offset forwardly, in the direction of the work feed, of the axes of the feed 65 rolls 2. A friction disk 8 axially mounted for rotation on an arm 10 is urged by a spring 12 against the periphery of a friction disk 14 secured on the shaft 6. A pulley 16 secured to the spindle of the feed roll 2 shown in the drawing drives a pulley 18, mounted on the spindle of the friction disk 8, by means of a belt 20. Thus the friction disk 8 is driven by rotation of the feed rolls

the drives the inking roll 4 through frictional contact with the friction disk 14 carried by the inking roll shaft 6. As the inking roll is rotated it dips into a receptacle 22 which may contain ink 1 maintained at a suitable level, the ink being applied by the roll to the marginal portion of a sole fed through the machine.

The sole S to which a coating of ink is to be applied around the marginal portion of its shank and forepart is presented to the machine as shown in the drawing, being gripped by the feed rolls 2 and fed in a curvilinear path in the direction of the arrow (FIG. 1) on the sole S by the feed rolls 2 assisted by the driven inking roll 4 into engagement with which the sole is urged by the feed rolls. The friction disks 8 and 14 are of such diameter as to cause the inking roll 4 to be driven substantially at the same peripheral speed as the speed of feed of the sole.

A plate 24 fixed on the machine has adjustably mounted thereon a bracket 26 which carries a pivotally mounted follower roll arm 28. The arm 28 is normally urged clockwise about its pivot 30, by a spring 32, into a raised position determined by engagement with an adjustable stop 34 attached to the plate 24. The spring 32 has one end attached to the arm 28 and its other end attached to a bracket 36 secured to the machine. A follower roll 38 mounted on the outer end of the arm 28 is engaged by the sole S as it is presented to the machine, the arm 28 yielding to take up the position shown in the drawing when the sole is positioned in the machine. By reference to the drawing it will be seen that the arm 28 is much more nearly parallel with the spring 32 in this position than in its raised position 28', the effect of the spring on the arm 28 in this position being much less than when the arm is raised. The arrangement is such that the effect of the spring 32 on the arm 28 is negligible, being sufficient only to hold the follower roll 38 in engagement with the sole edge so that when the machine is operated to feed the sole the roll 38 merely follows the edge contour without materially affecting the direction of feed.

As the toe end of the sole S is fed and operated on by the inking roll 4 the sole is moved out of engagement with the follower roll 38 and swung in a clockwise direction, as seen in the drawing, through a comparatively large angle. When the sole moves out of engagement with the roll 38 the arm 28 is thus freed for upward swinging movement to its position shown at 28', under the action of the spring 32, where it is in engagement with the stop 34.

The bracket 26 and stop 34 may be so adjusted to position the follower roll 38 that it is engaged by an edge portion of the sole as the sole is swung to the position shown at S'. The roll 38 which is held in its elevated position under comparatively strong spring pressure is effective to counteract the speed of swing of the sole but does not affect the pressure of the sole against the inking roll 4. As the sole continues to be fed, the arm 28 yields downwardly thereby reducing the effective force of the spring, so that when the marginal side and shank of the sole following the toe is being operated on the roll 38 merely follows the contour as hereinbefore described.

From what has been said it will be seen that the roll 38 is effective to catch a sole as it is swung about its toe end and thereby minimizes the possibility of it being swung out of contact with the inking roll 4, the roll 38 being adjustable for position to catch soles having varying shapes at the critical point of their swinging movement. The bracket 36 is provided with a series of holes through any one of which one end of the spring 32 may be anchored so that the angle of the spring relative to the arm 28 may be adjusted. Should the position of the follower roll 38 require adjustment to accommodate the shape of the work being operated on the stop 34 and/or the bracket 26 may be adjusted, the spring 32 being adjusted ac-

5 cordingly so that its effective force is not materially changed by adjustment of the follower roll position. Where particularly flimsy soles are to be operated on it may be desirable to reduce the force exerted by the spring 32 on the arm 28 by appropriate adjustment of the position of the spring 32.

10 It is a usual practice to use a sole margin ink having a resin base which tends to cause the ink to stick to the inking roll unless the ink is sufficiently agitated and it has been found that by rotating the inking roll under power it has the additional advantage of agitating the ink sufficiently to prevent it sticking to the roll.

15 When soles having more rounded toes are to be operated on, the work may be operated on more quickly by fitting larger feed rolls. For changing the speed of the inking roll accordingly the spring 12 may be disconnected from the arm 10 which is pivoted to the machine frame in a convenient position so that the friction disk 8 may be swung away from the friction disk 14 without removing the belt 20. The friction disk 8 may then be replaced with one having a suitable diameter. The simple drive connection between the feed rolls 2 and the inking roll 4 enables an operator to quickly and easily change one ink receptacle and inking roll for another. To disable the action of the roll 38, the arm 28 may be swung about its pivot 30, in an anticlockwise direction as seen in the drawing, to an out of the way position when rounded toe work is being operated on.

20 Having thus described my invention, what I claim as new and desire to secure by Letters Patent of the United States is:

25 1. In a machine for operating on shoe soles, means for feeding a sole in a curvilinear path such that the sole edge is progressively engaged around its contour with an operating tool, a member engageable with said edge in advance of the tool and mounted for movement toward and away from a predetermined position in the path of movement of the sole, and spring means urging said member toward said position with a force increasing progressively as the member approaches said position, said member being held away from said position by the sole as it is fed substantially lengthwise with the spring means exerting a relatively light force insufficient to deflect the sole from its normal path, said member thereafter being moved to said position where the spring means exerts a greater force when the sole is fed out of engagement with the member and is swung about its toe end whereupon the member in said position intercepts the swinging movement of the sole and is displaced by the sole 30 against a relatively heavy force to decelerate the swinging movement of the sole.

35 2. In a machine for operating on unattached soles, means for feeding a sole in a curvilinear path such that the sole edge is progressively engaged around its contour with an operating tool, a follower roll engageable with said edge in advance of the tool, means mounting the roll for movement in the path of movement of the sole, and spring means urging said roll into engagement with the sole edge and toward a predetermined position with a force increasing progressively as the roll approaches said position, said roll being held away from said position by the sole as it is fed substantially lengthwise with the spring means exerting a relatively light force insufficient to deflect the sole from its normal path, said roll 40 thereafter being moved to said position where the spring means exerts its maximum force when the sole is swung about its toe end, whereupon the roll in said position intercepts the swinging movement of the sole and is displaced against a relatively heavy force to decelerate the swinging movement of the sole.

45 3. In a machine for operating on unattached soles, means for feeding a sole edgewise in a curvilinear path such that the sole edge is progressively engaged around its contour with an operating tool, a follower roll engageable with said edge in advance of the tool, an arm mount-

ing the roll for movement in the path of movement of the sole as it is fed lengthwise, and spring means acting on said arm for urging said roll into engagement with the sole edge and toward a predetermined position with a force increasing progressively as the roll is moved toward said position, said roll being held away from said position by the sole against a relatively light force as the sole is fed substantially lengthwise, said roll thereafter being moved to said position when the sole is fed out of engagement with the roll and is swung about its toe end, whereupon the roll intercepts the swinging movement of the sole and is displaced against a relatively heavy force to decelerate the swinging movement of the sole.

4. In a machine for operating on unattached soles, means for feeding a sole edgewise in a curvilinear path such that the sole edge is progressively engaged around its contour with an operating tool, a follower roll engageable with said edge in advance of the tool, an arm mounting the roll for movement in the path of movement of the sole edge, an abutment limiting the movement of the arm for determining the position to which the roll may be moved in one direction, and spring means acting on said arm for urging said roll into engagement with the sole edge and toward said position with a force increasing progressively as the roll is moved toward said position, said roll being held away from said position by the sole against a relatively light force as the sole is fed substantially lengthwise, said roll thereafter being moved to said position when the sole is fed out of engagement with the roll and is swung about its toe end, whereupon the roll inter-

cepts the swinging movement of the sole and is displaced against a relatively heavy force to decelerate the swinging movement of the sole.

5. In a machine for operating on unattached soles, means for feeding a sole edgewise in a curvilinear path such that the sole edge is progressively engaged around its contour with an operating tool, a follower roll engageable with said edge in advance of the tool, an arm mounting the roll for movement in the path of movement of the sole, spring means acting on said arm for urging said roll into engagement with the sole edge and toward a predetermined position with a force increasing progressively as the roll is moved toward said position, and an adjustable abutment acting on said arm for varying said predetermined position thereby varying the maximum force exerted by said spring means, said roll being held away from said position by the sole against a relatively light force as the sole is fed substantially lengthwise, said roll thereafter being moved to said position when the sole is fed out of engagement with the roll and is swung about its toe end, whereupon the roll intercepts the swinging movement of the sole and is displaced thereby against a relatively heavy force to decelerate the swinging movement of the sole.
